UNITED STATES PATENT OFFICE.

JOHN A. CRAIG, OF PHILADELPHIA, PENNSYLVANIA.

DESIGN FOR WALL-PAPER.

Specification forming part of Design No. **7,940**, dated December 22, 1874; application filed November 9, 1874;
[Term of Patent 3½ years.]

To all whom it may concern:

Be it known that I, JOHN A. CRAIG, of Philadelphia, Pennsylvania, have invented a Design for Wall-Paper for covering walls, toy houses, play-blocks, &c., of which the following is a specification:

The accompanying print is an exact and full illustration of my design, it being an imitation of a brick wall as generally built. The ground is red, and is traversed horizontally by white lines, representing the mortar-courses. Between these horizontal lines are short vertical white lines, representing the joints, and

they are arranged at such intervals as to represent the courses "breaking joint" with each other, as is common in brick walls.

What I claim as my invention is—

A design for wall-paper, consisting essentially of a representation of a brick wall laid up with white mortar courses and joints, substantially as shown and described.

JOHN ALEXANDER CRAIG.
